TABLE

Peter M. Wege, East Grand Rapids, Mich., assignor to Metal Office Furniture Company, Grand Rapids, Mich., a corporation of Michigan

Application May 13, 1933. Serial No. 670,823

9 Claims. (Cl. 45—117)

The present invention relates to tables and more particularly to supporting columns therefor.

The main objects of the invention are to provide a table having a top, a base and a supporting column interposed and secured therebetween which is moderné in character; to provide a supporting column for a table of the character above indicated which is attractive in appearance; and, to provide such a table which is novel in character, convenient to assemble, rigid and sturdy in construction, and economical to manufacture.

An illustrative embodiment of the invention is shown in the accompanying drawing, wherein:

Figure 1 is an elevational view of a table employing the novel supporting column of the invention;

Figure 2 is a similar view, a portion of the table top being broken away and shown in section;

Figure 3 is a sectional view thereof on line 3—3 of Figure 2;

Figure 4 is an enlarged fragmentary sectional view of a portion of the supporting column on line 4—4 of Figure 5;

Figure 5 is a sectional view of a portion of the supporting column on line 5—5 of Figure 4;

Figure 6 is a sectional view showing the construction of the base on lines 6—6 of Figures 1 and 3;

Figure 7 is an enlarged fragmentary view of a portion of the supporting column and top on line 7—7 of Figure 2 and showing the manner of its attachment to the table top which is broken away and in section;

Figure 8 is a top plan view of the base; and Figure 9 is an elevational view of the base and a fragmentary portion of the supporting column.

Referring to the drawing in which like parts are designated by the same numerals in the several views, the table as shown in Figs. 1 and 2 generally comprises a base 1 preferably of substantial weight, a top 2, and a supporting column 3, parts of which are here shown as fabricated from sheet metal.

The base as shown in Figs. 3, 8 and 9 comprises a pair of transversely disposed feet 4, 5 preferably of sheet metal and here shown in Fig. 6 as comprising a U-shaped member 6 adapted to contact the floor, strengthening plates 7 secured to the vertically projecting flanged portions of the member 6 as by spot welding, and an inverted U-shaped member 8 capping the outer sides of the strengthening plates 7 to which plates it is secured in any suitable manner. Inasmuch as

the table disclosed herein is modernistic in type, the capping member 8 may, if desired, be chrome plated or otherwise similarly finished.

The table top 2 may be likewise formed from sheet metal and is provided with a peripheral 60 depending flange 9 either integrally formed therewith or otherwise secured thereto. This flange may if desired be likewise chrome plated or otherwise finished in keeping with the base in instances where the feet thereof are similarly 65 finished.

The supporting column interposed between the base and top comprises a series of four vertically disposed rods 10 whose opposite ends are screw threaded adapting them to be secured to the base 70 and top respectively as by the nuts 11 as best seen in Figures 5 and 7. These rods are in equally angularly spaced relation to each other as shown in Fig. 3.

A pair of elongated vertically disposed sheets 75 12, 13 as shown in Fig. 3 each have a central longitudinal panel disposed at an angle to its outer longitudinal edges which are curled to surround one of each of the spaced rods 10 and a pair of spaced elongated panels 14, 15 whose opposite 80 longitudinal edges are flanged inwardly are secured adjacent the edges of the central panels 12, 13 of the elongated sheets as by spot welding.

Split sleeves 16 embracing each curled portion of the elongated sheets 12, 13 as best shown in 85 Figures 3 and 4 are adapted to be slid thereon and may be likewise chrome plated in instances where other portions of the table are similarly finished.

It will thus be seen that a table moderné in 90 character is herein shown and described whose supporting column is attractive in appearance, novel in character and rigid and sturdy in construction, and that the table is convenient to 95 assemble and economical to manufacture.

While but one specific embodiment of this invention has been herein shown and described, it will be understood that numerous details of the construction shown may be altered or omitted 100 without departing from the spirit of this invention as defined by the following claims.

I claim:

1. In a structure of the class described, a supporting column adapted to be interposed and 105 secured between a base and a top comprising a series of four spaced rods whose lower ends are adapted to be secured to the base and whose upper ends are adapted to be secured to the top, and a pair of elongated sheets whose opposite longi- 110

- tudinal edges are each curled to encircle one of said spaced apart rods.
2. In a table having a base, a top, and a supporting column interposed and secured between the base and top comprising a series of four spaced apart vertically disposed rods whose lower ends are secured to the base and whose upper ends are secured to the top, and a pair of elongated sheets whose opposite longitudinal edges are each curled to encircle one of said spaced apart rods.
3. In a structure of the class described, a supporting column adapted to be interposed and secured between a base and a top comprising a series of four rods whose lower and upper ends are adapted to be secured to the base and top respectively and in equally angularly spaced relation to each other, and a pair of elongated sheets whose opposite longitudinal edges are each curled to encircle one of said spaced apart rods.
4. In a structure of the class described, a supporting column adapted to be interposed and secured between a base and a top comprising a series of four rods whose lower and upper ends are adapted to be secured to the base and top respectively and in equally angularly spaced relation to each other, and a pair of elongated sheets whose medial portion is turned inwardly and whose opposite longitudinal edges are each curled to encircle one of said spaced apart rods.
5. In a structure of the class described, a supporting column adapted to be interposed and secured between a base and a top comprising a series of four rods whose lower and upper ends are adapted to be secured to the base and top respectively and in equally angularly spaced relation to each other, a pair of elongated sheets whose medial portion is turned inwardly and whose opposite longitudinal edges are each curled to encircle one of said spaced apart rods and a pair of spaced elongated panels whose outer longitudinal edges are each secured adjacent one side of the medial portion of the sheets.
6. In a structure of the class described, a supporting column adapted to be interposed and secured between a base and a top comprising a series of four rods whose lower and upper ends are adapted to be secured to the base and top respectively and in equally angularly spaced relation to each other, a pair of elongated sheets each having a central longitudinal panel disposed at an angle to its outer longitudinal edges which are each curled to surround one of said spaced apart rods, and a pair of spaced elongated panels whose opposite longitudinal edges are each flanged inwardly and secured adjacent the edges of the central panels of the elongated sheets.
7. In a structure of the class described, a supporting column adapted to be interposed and secured between a base and a top comprising a series of four spaced rods whose lower ends are adapted to be secured to the base and whose upper ends are adapted to be secured to the top, a pair of elongated sheets whose outer longitudinal edges are each curled to encircle one of said spaced apart rods and split sleeves embracing each curled portion of the elongated sheets.
8. In a structure of the class described, a supporting column adapted to be interposed and secured between a base and a top comprising a series of four rods whose lower and upper ends are adapted to be secured to the base and top respectively and in equally angularly spaced relation to each other, a pair of elongated sheets whose medial portion is turned inwardly and whose outer longitudinal edges are each curled to encircle one of said spaced apart rods, a pair of spaced elongated panels whose opposite longitudinal edges are each secured adjacent one side of the medial portion of the sheets, and split sleeves embracing each curled portion of the elongated sheets.
9. In a table having a base, a top, and a supporting column interposed and secured between the base and top comprising a series of four rods whose lower and upper ends are secured to the base and top respectively and in equally angularly spaced relation to each other, a pair of elongated sheets each having a central longitudinal panel disposed at an angle to its outer longitudinal edges which are each curled to surround one of said spaced apart rods, and a pair of spaced elongated panels whose opposite longitudinal edges are each flanged inwardly and secured adjacent the edges of the central panels of the elongated sheets.
